MARTIN A. GREEN, OF PHILADELPHIA, PENNSYLVANIA.

STEAM-ENGINE.

1,045,698.

Specification of Letters Patent. Patented Nov. 26, 1912.

Application filed October 14, 1911. Serial No. 654,771.

To all whom it may concern:

Be it known that I, MARTIN A. GREEN, a citizen of the United States, and a resident of Philadelphia, in the county of Philadelphia, State of Pennsylvania, have invented a new and useful Improvement in Steam-Engines, of which the following is a specification.

My invention is an improvement in reciprocating steam engines, and has for its object the provision of simple economical, and easily operated means for varying the clearance at each end of the cylinder, in order to increase or diminish the compression, and without affecting the total length of the cylinder or the total length of the piston.

In the drawings:—Figure 1 is a vertical longitudinal section of an engine constructed in accordance with the improvement, and Fig. 2 is a similar view of a modified form.

It has been found practically impossible to design an engine of the reciprocating type, either stationary, locomotive or marine, with proper clearance to give the proper amount of compression to suit all conditions, whether condensing or non-condensing, variable steam pressures and variable speeds, without adjustable exhaust valves (when exhaust valves are used). It is just as impossible to design an engine of the center discharge or exhaust type to produce the same effects without an adjustment to increase or diminish the clearance, so as to regulate the compression to suit all conditions.

When an engine is running condensing, a vacuum is formed in the cylinder and practically all of the steam is withdrawn therefrom, when the piston uncovers the exhaust ports. When the engine is running non-condensing some steam will remain in the cylinder after the ports have been uncovered, and if the clearance between the piston and the cylinder heads is slight, too great an amount of steam will remain at atmospheric pressure, and there will be danger that the cylinder heads will be broken or blown out.

In the present invention, a means is provided for increasing or diminishing the clearance at the ends of the cylinder, in order to obtain the proper compression at the ends thereof. When the improved engine is running condensing, the clearance can be reduced to a minimum, because the clearance that would naturally occur if ex-

haust valves were used, will be saved. In the usual type of engine where steam admission and exhaust valves are used, the exhaust valves are at the ends of the cylinder and the said valves must begin to open long before the piston is at its journey's end in either direction, thus cutting down the mean effective pressure in the cylinder, and at the same time permitting (when the exhaust valves are opened) the most effective portion of the steam to exhaust into the atmosphere, that is, that portion of the steam which is nearest the ends of the cylinder and as a consequence the hottest.

In the improvement, the piston acts as an exhaust valve and the exhaust occurs after the piston has traveled practically the entire length of its stroke, and since the exhaust occurs near the longitudinal center of the cylinder, the least effective portion of the steam, that is, the coolest, is ejected, together with a considerable portion of the condensed steam, while the hottest and the most effective portion thereof is retained for compression.

In the improvement, neither the length of the piston nor the length of the cylinder is affected. For this reason it does not matter at what point the engine cuts off, or what method of adjustment is used, since the piston always opens the ports in the center of the cylinder at the right and proper time to relieve the exhaust steam. This is true whether the adjustment is in the piston or in the cylinder head.

The improved engine is cheaper in first cost, since the cylinder is of such form and design that it may be cheaply cast, and cheaply fitted up, and since exhaust valves and exhaust apparatus are eliminated. It is also more economical in the operation and upkeep because of the simpler construction and fewer parts. In addition since the steam follows the piston to approximately its journey's end practically all of the expansion of the steam is utilized with one cylinder, thus making a one cylinder engine as economical and as effective as a compound engine, and without the expense of a second cylinder.

In the embodiment of the invention shown in Fig. 1, the cylinder 1 of the engine is supported by a base or pedestal 2. The cylinder is provided intermediate its ends, and at approximately its longitudinal center, with an annular series of exhaust open-

ing or slots 3, and with an annular chamber 4 in the cylinder wall with which the slots 3 communicate. The exhaust chamber extends upon both sides of the series of slots toward the ends of the cylinder, and forms a steam jacket, acting to prevent condensation at this point, and to retain the steam in heated condition. The chamber opens into the pedestal as shown at 4^a. The ends of the cylinder are closed by heads 5 and 6, the former being secured in place by cap screws 7, and the said heads 5 and 6 are cup-shaped as shown, and the cylinder is provided with inlet ports 8 and 9 at each end, and adjacent to the head. The said openings 8 and 9 communicate with a chamber 10 at the upper part of the cylinder, and extending longitudinally thereof, through valve openings 11 and 12, respectively, each opening being encircled by a seat with which the inlet valves 13 and 14, respectively, coöperate. At the lower part of the cylinder, relief ports 17 and 18 are provided, each of which is provided with a valve casing 15 and 16, respectively, and the casings are controlled by valves 19 and 20, respectively. Each valve is held in closed position by means of a spring 17^a, and the tension of each spring may be adjusted by means of the stem 18^a bearing against the outer end of the spring. The casings also communicate with each other by means of a pipe 21. The valves 19 and 20 are relief valves and are designed to prevent injury to the cylinder from overpressure. Should the pressure in either end of the cylinder pass a predetermined point, determined by the tension of the spring, the valves will open, permitting a portion of the fluid to escape, thus relieving the pressure. The point at which the valves open may be regulated by means of the springs. A valve stem 22 is connected to each valve 13 and 14, and each stem extends upwardly through a casing 23 secured to the cylinder over an opening 24 leading from chamber 10 before mentioned. Each casing 23 is provided with a transverse passage 25 extending parallel with the axis of the cylinder, and each stem is provided with a stirrup or hanger 26 at the said opening. A roller 27 is journaled in each stirrup, and a spring 28 is arranged between the upper end of each stirrup and a cap 29 in the top of the casing. Each cap is engaged by a screw 30 threaded through the top of the casing, and by means of the screws the tension of the springs may be adjusted to vary the pressure on the valves. A slide bar 31 is movable through the openings 25, and the said bar is provided with a cam 32 coöperating with each roller for lifting the valve connected therewith. The bar is connected at one end to a crank arm 33 on a shaft 34 by means of a link 35, and in each casing the bar

is supported by a plurality of series of balls 36 moving in registering grooves in the bar and in a cap plate 37 in the opening 25.

Each cap plate 37 is arranged in the opening 25, and each end of each plate is flanged downwardly, as indicated at 38. A strap 39 is secured to the edge of each flange by screws 40, and the inner edge of each strap engages beneath a shoulder 41 on the casing to hold the cap plate in place. The cams 32 are so arranged that the valves 13 and 14 will be lifted alternately, and the shaft 34 is rotated from the engine at a speed such that the valves will be operated at the proper time. Each of the heads 5 and 6 is, as before stated, cup-shaped, so that a recess is formed at each end of the cylinder in the head. A movable head 43 or 44 is arranged in the recesses of the respective heads 5 and 6, and each head fits closely in the recess and is provided with suitable packing rings 45^a. Each head is concavo-convex and is arranged with its convex face inwardly, and the fixed heads are shaped to fit the movable heads. A screw threaded pin or bolt 45 is threaded through a central opening in head 43, and at each side of the head is provided with a collar 46. The bolt is reduced at its outer end and the reduced portion passes through a central opening in the fixed head 5 and is engaged by a nut 47. The movable head 44 is provided with a central opening for receiving the piston rod 48 and a sleeve 49 which encircles the rod. The sleeve is externally threaded adjacent to the head, and the central opening of the head is provided with a thread fitting the thread of the sleeve. The sleeve is prevented from longitudinal movement by means of an enlargement 49^a on the sleeve, the said enlargement being received within a recess 6^a of the adjacent head 6. Packing plates 49^b are arranged within the recess, the said plates being shaped to fit the enlargement, and a plate 49^c is secured to the inner face of the head 6 over the recess. The sleeve may be engaged by means of a spanner or other tool to turn the same to move the head 44 toward or from the center of the cylinder.

The piston is composed of two sections 50 and 51, spaced apart from each other, and arranged on a reduced portion 52 of the rod. The outer face of each section is shaped to fit the inner face of the adjacent movable head, and the said sections are held in spaced relation by means of a sleeve 50^a encircling the reduced portion of the rod between the heads. Each section is provided with packing rings 50^b, and a shell 51^a is arranged between the heads, the outer face of the shell bearing against the inner face of the cylinder. The shells 50^a and 51^a hold the sections in proper position, and prevent the admission of steam between the sections.

When the piston or plunger is at the end of its stroke in either direction, the sections or heads 50 or 51 of the piston uncover the exhaust openings or slots 3 as shown in Fig. 1. The movable heads 43 and 44 of the cylinder, are of less diameter than the piston, so that the actual length of the cylinder is not affected by the adjustment of the heads, but only the clearance between the ends of the piston and the ends of the cylinder. The manner of adjustment may be by other means than movable heads for the cylinder. As for instance in Fig. 2, the clearance is varied by means of movable heads in the piston or plunger. The cylinder 55 is provided with a central annular series of exhaust openings 56, and with inlet openings 57 and 58 at the ends of the cylinder and the openings 56 communicate with the annular chamber 59, which corresponds to chamber 4. The chamber 59 communicates with the atmosphere by means of a passage 60.

The piston shown in Fig. 2 is composed of a sleeve 61, having a central transverse web 62, to which is connected the piston rod 63. The sleeve 61 is approximately one-half the length of the cylinder, so that the passages 56 are uncovered just as the piston reaches the end of its stroke in either direction. A movable head is arranged upon each side of the web 62, each head 64 and 65 being slidable in the sleeve 61. The head 64 is provided with a central opening for receiving a bolt 66, threaded into a socket 69 in the adjacent end of the piston rod. The bolt is provided with a collar 67 on the inner side of the head, and a jamb nut 68 is provided with a central opening for receiving the piston rod 63, and bolts 70 are threaded into bosses 71 on the head. Each bolt is passed through the web 62 and is provided with a collar 70a on one side of the web, and with a jamb nut 72 on the other side. The heads may thus be adjusted toward and from the web and the inlets 57 and 50 open into the space between the ends of the cylinder and the movable heads. The head 64 is adjusted by turning the bolt 66, and the head 65 by turning the bolts 70. The operation is the same as in the construction of Fig. 1, and the valves co-operat-

ing with the inlet ports 57 and 58 may be of any usual or desired construction.

I claim:—

1. In a double acting, reciprocating, center discharge, steam engine the combination with a cylinder having inlet ports at its ends, and an annular chamber intermediate its ends and at its approximate center and an annular series of exhaust ports opening into the chamber, and a piston adapted to over run and control said exhaust ports, a rod connected with the piston and extending through one head of the cylinder, the cylinder having each of its heads internally recessed, said recesses being cylindrical and of equal cross section throughout and of less cross section than the piston, a head movable in each of the recesses, means for moving the head in the recesses remote from the piston rod, a sleeve encircling the piston rod and rotatable thereon and extending through the adjacent head of the cylinder and the adjacent movable head and having a threaded portion engaging the said movable head to move the said head when the sleeve is rotated.

2. In a double acting reciprocating steam engine, the combination of a cylinder and a piston operating within the cylinder, each of the said elements having heads, the heads of one of the said elements being adjustable in the direction of length of the cylinder, whereby the clearance may be varied to increase or diminish the compression, the movable heads being in fixed relation to the elements with which they are associated in their different adjustments.

3. In a double acting reciprocating steam engine, the combination of a cylinder and a piston movable therein, each of the said elements having heads, sundry of the said heads being adjustable in the direction of length of the cylinder to vary the working length of the cylinder at each end thereof, said adjustable heads being in fixed relation to the elements with which they are respectively associated in their different adjustments.
